APPARATUS FOR DEPOSITING GRANULAR MATERIAL IN A WELL BORE

Guss F. Abendroth, Houston, Tex., assignor, by mesne assignments, to Esso Research and Engineering Company, Elizabeth, N. J., a corporation of Delaware

Application November 8, 1951, Serial No. 255,447

2 Claims. (Cl. 166—51)

The present invention is directed to a method and apparatus for depositing granular material in a well bore. More particularly, the invention is directed to a method and apparatus for forming a gravel pack in a cavity in a producing formation.

The invention may be briefly described as involving a tool for depositing granular material in a well bore which comprises a mandrel open at each end which is adapted to be connected to a tubing string. The mandrel defines a plurality of spaced apart ports between an upper and lower end of the mandrel with the spaced apart ports being adjacent an upper end and at a point on the mandrel no higher than a mid-point thereof. A packer is mounted on the mandrel for closing an upper of said ports on movement of said mandrel with respect to the packer when the latter is set. The mandrel is provided with a stop member below the packer to limit the travel of the mandrel relative to the packer, in an upward direction. An inner barrel open at each end is arranged in the mandrel and is rigidly connected thereto at an upper end. The inner barrel is sealed to the mandrel at a lower end thereof so that the inner surface of the mandrel and the outer surface of the inner barrel define an annulus for flow of fluid therethrough. The flow of fluid through the annulus is controlled by the position of the packer with respect to the upper of the spaced apart ports.

The invention also involves a method for depositing granular material in a cavity in a formation adjacent a well bore in which a suspension of granular material and a liquid vehicle is flowed downwardly through a pipe or tubing string in the well bore to deposit granular material therein. After granular material has been deposited to a sufficient extent in the well bore, the flow of suspension is terminated and an annulus between the pipe string and the well bore is isolated at a lower point in the well bore against upward flow. Liquid is then pumped downwardly in the well bore under a pressure sufficiently high to wash the granular material into the cavity while the pipe string is being manipulated upwardly and downwardly in said well bore.

The present invention will be further illustrated by reference to the drawing in which

Fig. 1 illustrates the steps employed in gravel packing in accordance with my invention;

Figs. 2 and 3 show an embodiment of the apparatus employed therefor; and

Fig. 2a is a view in elevation illustrating the releasing assembly for the packer shown apart from the apparatus of Fig. 2.

Referring now to the drawing and particularly to Fig. 1, a perforated cased well bore 11 is shown with the device generally indicated as 12 being lowered therein. The device 12 is attached to a tubing or pipe string. The device embodies a mandrel 12a defining upper ports 14 and lower ports 15. The mandrel 12a is provided with a stop member 16 above the lower ports 15 to limit the travel of mandrel 12a with respect to a packer 17

2

arranged thereabove. Inside the mandrel 12a is an inner barrel 18 which is rigidly attached to the upper end of the mandrel by a connection means 19 which may be a threaded coupling or the inner barrel 18 may be connected to the mandrel 12a by welding. The lower end of the inner barrel 18 is sealed to the mandrel 12a by sealing means 20, such as O-rings. It will be noted that the mandrel 12a and the inner barrel 18 define an annulus A through which fluid may flow. It will be noted in step 1 of Fig. 1 that the flow upwardly in the cased well bore 11 by displacement of fluid as the tool is lowered is as indicated by the arrows through the inner barrel 18 and through the perforations 15 into the annulus A and thence through the ports 14 into an annulus A' between the cased well bore 11 and the pipe or tubing string 21 to which the mandrel 12a is attached by means not shown.

Referring to step 2, it will be noted that the packer 17 has been arranged below the ports 14 and above the ports 15. It will be noted in step 2 that cavity 30 in a producing formation 31 had previously been formed and that the casing 11 is provided with perforations 32 adjacent the formation 31.

In step 3 of Fig. 1 a suspension of finely divided granular, particulate material is flowed downwardly through the tubing or pipe string 21 and thence through the inner barrel 18 and into the lower portion of the cavity 30, a bed of granular, particulate material 33 accumulating therein as shown. The suspension of granular material is in a liquid vehicle, such as salt water or oil, and as the vehicle deposits the granular material in bed 33 the liquid with some granular material remaining in it flows upwardly through the annulus A' and thence by virtue of the position of the packer 17 through the perforations 15 into the annulus A and outwardly back into the annulus A' through the ports 14 and thence to the earth's surface through the usual well head equipment.

In step 4 of the method in accordance with my invention the flow of granular material in the liquid vehicle has been terminated and salt water, for example, is then flowed downwardly through the tubing or pipe string 21 into the inner barrel 18 causing the washing downwardly of the apparatus of the present invention into the gravel which has been deposited in the lower end of the well bore, the packer 17 remaining fixed to the casing 11 and the apparatus 12 moving slidably downwardly therethrough. Meanwhile the flow is, as indicated by the arrows, upwardly through the annulus A' and thence through the port 15 into the annulus A and then outwardly through the ports 14 into the annulus A' and thence to the well head.

In step 5 of the drawing illustrating my invention the tubing string 21 is being manipulated upwardly and downwardly in the cased well bore 11 through the packer 17 while the flow of salt water is continuing downwardly through the inner barrel 18 and then outwardly through the ports 32 into the cavity 30 causing the bed 33 to fill substantially completely the cavity 30. The flow of fluid is outwardly into the cavity 30 and thence into the formation 31. By virtue of the position of the packer 17 while washing the granular material into cavity 30 the ports 14 are closed against flow into the annulus A'. Also by virtue of the position of the packer 17 with respect to the mandrel 12a flow through the ports 15 is also terminated. Since there is a tendency for finely divided particulate material to form bridges in the well bore on deposition therein and since pressure will not cause granular material to flow, in the practice of my invention the manipulation of the tubing or pipe string upwardly and downwardly, as indicated in step 5, causes the granular material to wash outwardly into the cavity 30 and to fill same and to form

3

a granular pack in the cavity 30 as well as within the cased well bore 11.

Referring now to Figs. 2 and 3, it will be seen that the mandrel 12a is provided with a collar 13 which allows the mandrel 12a to be connected to a tool joint 10 which, in turn, may be connected to a tubing string by internal threads 9. The joint 10 is provided with threads 8 which mate with the threads 19 on wash pipe or barrel 18 and allow the latter to be rigidly connected to the joint 10. As illustrated, the mandrel 12a is provided with a plurality of ports 14 at an upper end thereof and has slidably mounted thereon a packer 17 which may be of the conventional type with swab cups 40 at an upper and a lower end of the packer, collars 41 and a gripping means 42 which may be biased outwardly. The packer means of packer 17 is indicated by the numeral 43 and is expanded outwardly when the gripping means 42 moves into operative position. The mandrel means 42 moves into operative position. The mandrel is provided with a stop means 16 which is shown in Fig. 3 as a coupling but this may be an auxiliary stop member arranged on the mandrel 12a at a point below the packer 17 and above the ports 15 which are arranged on the mandrel 12 below a mid-point thereof and preferably adjacent a lower end. The lower end of the mandrel 12a is provided with a tool joint 44 to which may be connected sections of pipe tubing or pipe.

While the present invention has been described and illustrated for use in a cased well bore, it is to be understood that it may be used equally as well in an uncased well bore. The packer 17 is releasably mounted on a mandrel 12a, such as by J-slots 45 and pin 45a, and the like to allow the mandrel 12a to be moved therethrough. While J-slots may be used for convenience, it is to be understood that other releasable means may be employed for mounting the packer 17 on the mandrel 12a.

The nature and objects of the present invention hav-

ing been completely described and illustrated, what I wish to claim as new and useful and to secure by Letters Patent is:

1. A tool for depositing granular particles in a well bore which comprises, in combination, a mandrel open at each end, adapted to be connected to a tubing string, provided with a plurality of spaced apart ports between the upper and lower end of said mandrel, said mandrel being provided with a packer releasably mounted on an exterior surface of said mandrel, being movable for closing and opening of an upper of said ports on movement of said mandrel with respect to said packer when set, a stop member on said mandrel for restricting upward travel of said mandrel, an inner barrel open at each end rigidly connected thereto at an upper end above an upper of said ports and sealing means in a lower end of said mandrel between said mandrel and said barrel below a lower of said ports for causing a seal therebetween, said mandrel and said barrel defining an annulus adapted for flow of fluid therethrough, the flow through the annulus through said ports being controlled by the position of the movable mandrel with respect to said packer.
2. Apparatus in accordance with claim 1 in which the mandrel defines spaced apart ports at an upper end and at a point on the mandrel no higher than at a mid-point thereof.
